UNITED STATES PATENT OFFICE.

LOUIS SEVERUS, OF CHICAGO, ILLINOIS, ASSIGNOR TO ART LAMP MANUFACTURING COMPANY, OF CHICAGO, ILLINOIS.

DESIGN FOR A LAMP BRACKET.

Application filed April 3, 1925. Serial No. 12,994. Term of patent 3½ years.

To all whom it may concern:

Be it known that I, LOUIS SEVERUS, a citizen of the United States, residing at Chicago, in the county of Cook and State of Illinois, have invented a new, original, and ornamental Design for a Lamp Bracket, of which the following is a specification, reference being had to the accompanying drawings, forming part thereof.

Fig. 1 is an edge elevation.

Fig. 2 is a side elevation.

I claim:

The ornamental design for a lamp bracket as shown.

LOUIS SEVERUS.
